UNITED STATES PATENT OFFICE.

HERBERT C. SMITH, OF GASTON, OREGON.

LUBRICATOR.

1,277,656.

Specification of Letters Patent.

Patented Sept. 3, 1918.

Application filed October 25, 1917. Serial No. 198,428.

To all whom it may concern:

Be it known that I, HERBERT C. SMITH, a citizen of the United States, residing at Gaston, in the county of Washington, State of Oregon, have invented a new and useful Improvement in Lubricators, of which the following is a specification, reference being had to the accompanying drawings.

My invention relates to a class of devices used to convey lubricant from a convenient depository to desired parts of a mechanism.

The object of my invention is to provide a device particularly adapted to automatically discharge lubricant upon the gear teeth of a traction mechanism. I accomplish this object, as well as others, by the construction, combination and arrangement of parts, illustrated in the accompanying drawings, which form a part hereof.

Figure 1 is an elevation partly in section on line 1—1 of Fig. 2.

Fig. 2 is a sectional view on line 2—2 of Fig. 1.

Fig. 3 is a side elevation of the device in operative position upon a chain drive mechanism.

Like letters and numerals refer to like parts in all figures.

A is a wheel with outer gear teeth 4. A' is a similar wheel in a form showing chain drive mechanism, with teeth 4'. B is a chain arranged to engage the wheel teeth 4'. C is a portion of a frame arranged suitably near the wheel A. A brush 5 is secured to the frame C by bolts 6 and it extends transversely to the wheel, above and in alinement with the teeth 4. The brush is provided with longitudinally disposed bristles 7 along each of its lower sides, said bristles extending into the opposing inter gear tooth space of the wheel. The brush 5 has an interior longitudinal recess 8, from which extends a series of lower vertical passages 9 between the rows of bristles 7. A pipe 10 is arranged to extend from the recess 8 to a lubricator cup 11 which is provided with a threaded compressing cap 12. It is intended that the lubricant to be employed shall be of the common type of grease or compounds which do not flow.

It will now be apparent that when my device is in operative position as disclosed, the bristles engage the gear teeth 4 as the wheel rotates beneath them. When it is desired to lubricate the teeth the compressor

cap is operated to force a desired amount of non-flowing lubricator into the brush recess 8 from whence it passes downwardly through the passages 9 and between the rows of bristles. As the wheel rotates, the forward row of bristles engages the approaching side of a gear tooth and tends to remove dust and foreign matter from it. Thereafter the second row of bristles, having lubricant upon their inside surfaces, engages the same side of the gear tooth and deposits the congealed form of lubricant upon it. This operation continues successively as to each gear tooth while the wheel is rotating. I contend that one rotation of the wheel will cause it to receive and retain an even and sufficient lubrication by means of my device. It tends to keep the gear teeth clean before deposit of the lubricant, prevents waste of the latter, and permits the discharge of a uniform and pre-determined amount of lubricant, by means of the forced feed from the cup. I have contemplated the application of my device particularly to motor driven vehicles, such as tractors, when they are provided with the usual type of chain drive. It may, however, be adapted successfully to other types of mechanism requiring the exterior application of congealed lubricant to parts moving similarly to those illustrated. I contend that I have provided a new device to accomplish these objects in a most simple and easily applied form and that the lubricator is cheaply made and installed, also that it will economize in the amount of lubricant used, all of which makes it a useful article. I have shown the brush above the chain in Fig. 3 but it may be arranged to engage that portion of the teeth just after the chain engagement therewith ceases, or just before the chain engages the teeth. The engagement by the brush is illustrated in Fig. 2.

Having substantially described my device, I claim:

1. In a device of the character described a lubricating member the same being a brush having a longitudinal row of bristles on each of its outer lower sides a recess in the brush with a series of vertical passages extending downwardly from the recess between the bristle rows and a lubricator receiving passage extending from the recess without the brush, said recess and passages being of a form and arrangement adapting them to re-

ceive into and through them a congealed lubricant only under pressure from without, substantially as described.

2. In a device of the character described the combination of a brush having a longitudinal row of bristles on each of its outer lower sides a recess in the brush with a series of vertical passages extending downwardly from the recess between the bristle rows and a lubricator receiving passage extending from the recess without the brush, said recess and passages being of a form and arrangement adapting them to receive into and through them a congealed lubricant only under pressure from without, with a lubricator cup provided with a discharge pipe extending therefrom into the said brush receiving passage and means about the cup to force its contents into said passage substantially as described.

3. In a device of the character described the combination of a brush having a longi-

tudinal row of bristles on each of its outer lower sides a recess in the brush with a series of vertical passages extending downwardly from the recess between the bristle rows and a lubricator receiving passage extending from the recess without the brush, said recess and passages being of a form and arrangement adapting them to receive into and through them a congealed lubricant only under pressure from without, a lubricator cup provided with a discharge pipe extending therefrom into the said brush receiving passage and means about the cup to force its contents into said passage, with the gear teeth of a mechanism which teeth the brush bristles are arranged to engage while the teeth are moving, substantially as described.

HERBERT C. SMITH.
